PROCESS FOR PRODUCTION OF GASOLINE
FROM PETROLEUM HYDROCARBONS

Arthur D. Smith, Chicago, Ill., and Norman M. Ranstead, Whiting, Ind., assignors to Jenkins Petroleum Process Company, Chicago, Ill., a corporation of Wisconsin

Application June 19, 1929. Serial No. 372,145

6 Claims. (CL 196—60)

This invention relates to certain improvements in the treatment of petroleum hydrocarbons, and particularly to a process for the continuous separation of natural or gasoline existent therein, concurrently with the continuous production from the non-gasoline fractions thereof, of highly volatile cracked and/or specially converted high benzole equivalent gasoline, as the sole objectives.

In the ordinary treatment of crude petroleum, or a cracking stock containing appreciable quantities of natural gasoline, the latter product is removed by fractional distillation under atmospheric pressure, and various selective fractions directly or indirectly obtained from the remainder, are separately and independently subjected to cracking conditions involving relatively high temperatures and pressures; such separate and independent treatments not only producing the desired gasoline objectives, but also products of relatively low market value, such as distillate, fuel oil and/or coke and gas, in varying quantities dependent upon the method of cracking employed.

While cracking of intermediately produced recycle stock is more or less successfully accomplished in many cracking processes, the conversion of relatively light distillates into desirable gasoline fractions, in apparatus primarily designed for cracking products of relatively high specific gravity, is commonly attended with difficulty. The prevention of fuel oil as an end product of cracking has been variously attempted: Thus; either a preliminary distillation at atmospheric pressure, whereby an easily convertible distillate is obtained, or severe cracking conditions have been suggested; either method being uneconomic in heat consumption, and producing large quantities of coke of relatively low market value. It has been further proposed to filter, centrifuge or precipitate suspended carbon or high molecular weight complexes from the degraded still contents, returning the clarified stock to the system for further conversion, but such methods are open to the objection of handling large quantities of material, attendant with frequent coggings of the apparatus, and large losses of radiant heat. A general object of this invention is to continuously and economically effect, through the application of one primary source of heat, and the subsequent utilization of the waste and indirect energy therefrom, the complete refining of a petroleum hydrocarbon into superior gasoline without production of distillate or fuel oil end-products; and to accomplish such objective with a minimum formation of

fixed gas, free carbon and/or amorphous derivatives thereof.

A further general objective of the invention is to effect the continuous separation of the natural gasoline content of a crude oil or cracking stock by simple fractionation, concurrently with, and by the agency of the indirect heat from a combination liquid and vapor phase process; wherein the reduced stock from such primary separation is continuously cracked in liquid phase, the heavier by-products from such liquid phase treatment progressively cracked in like phase, the relatively light, non-gasoline by-products from such liquid phase treatment continuously cracked in vapor phase, and the less preferred products from such vapor phase treatment continuously cracked in like phase; with gasoline of preferred market specifications as the sole objective.

An additional general objective of the invention is to effect the above described separation of natural gasoline and the respective conversions in liquid and vapor phase at temperatures and under pressures best suited for such treatments; as to produce ultimate maximum gasoline yields coordinated to the instrumentality of the heat initially applied to the liquid phase treatment.

In such liquid phase treatment, the previously mentioned preheated reduced stock, together with other similarly heated intermediates to be presently described, is continuously charged to a cracking still, where continuous cracking is effected in liquid phase at a temperature and under a pressure best suited for ultimate maximum gasoline production; such ultimate yield being a concurrent function of immediate gasoline production and the accompanying degree of degradation of the reacting medium.

A highly important object of the invention is therefore, to continually subject such cracking stock in a still, while maintaining positive cyclic circulation therein, to a temperature and under pressure best suited for immediate maximum gasoline production compatible with a controlled degradation of the reacting still content; preferably regulating such degradation, by operating under such temperature and pressure, as to produce a predominance of complex hydrocarbon polymerides soluble in the reacting medium, rather than free carbon; and to achieve such objective at a temperature and under a pressure less than otherwise possible by reason of a uniform absorption of heat, approaching the vanishing point of differential in all portions of the

95

100

105

110

liquid still content, due to such positive cyclic circulation there maintained.

Another important object of the invention is to continuously remove from the still, while effecting continuous cracking and maintaining positive liquid cyclic circulation therein, a sufficient quantity of controlled degraded stock to a zone of reduced pressure, as to produce therein after separation and removal therefrom of a substantial portion of such degraded stock as recycle vapor, a further reduced residuum so super-saturated with difficultly soluble high molecular weight complex polymerides as to cause partial separation thereof.

15 An additional object of the invention is to continuously charge to the still, while maintaining positive liquid cyclic circulation therein, with accompanying continuous production and release of gasoline, return of reflux and withdrawal of degraded stock in the manner previously mentioned, a sufficient quantity of preheated charging stock as to maintain in such still a substantially constant liquid level.

A further object of the invention is to continuously introduce to such still with such preheated charging stock, an adsorptive coagulant, such as lime, beauxite or other material producing a like effect; to further continuously release therefrom into a low pressure vapor separator such above described degraded stock, together with its proportionate quantity of adsorptive coagulant; originally introducing an amount of such coagulant, and continuously withdrawing such a quantity of degraded stock, as to produce in such vapor separator after reduction of pressure therein and removal of the vaporized recycle stock fractions therefrom, a further reduced residuum and a partially coagulated, suspended complex of hydrocarbon polymerides of high molecular weight, free carbon and adsorptive coagulant; with such coagulant originally introduced in such quantity, as to effect additional partial coagulation upon further separation of less soluble complexes by reduction in temperature of the further reduced residuum.

50 A correlative object of the invention, in conjunction with the steps described in the preceding paragraph, is to originally continuously introduce a sufficient quantity of lime and/or other adsorptive coagulant, as to impart to the previously mentioned complex a specific gravity insufficient to substantially affect its suspension in the previously mentioned further reduced residuum, but of such differential from the latter as to cause 55 eventual precipitation from such residuum in a zone of repose, and at the same time a porosity and absence of gummy and sticky qualities, ordinarily causing clogging in subsequent filtering or centrifuging operations.

60 An additional object of the invention is to initially substantially evaporate in a vaporizing zone, heated by an exchanger through which the previously described degraded stock is constantly circulated, the intermediate distillate dephlegmated from the crude gasoline produced under liquid phase treatment; to progressively similarly evaporate in such zone by such previously described source of heat the corresponding intermediate produced under vapor phase treatment of the first intermediate; and to continuously maintain a vapor pressure in such zone of vaporization and the thereto unrestrictedly connected vapor phase converter, functional of such substantial vaporization; as best suited for the maximum production of anti-knock high benzole

equivalent gasoline by the contained heat of the degraded stock producing such substantial vaporization, and the waste heat available from the liquid phase cracking furnace producing such vapor phase conversion.

80 A summarized object of the invention is the concurrent, ultimate, maximum production of straight run gasoline, highly volatile cracked gasoline produced under liquid phase, and high benzole equivalent gasoline produced under vapor phase from a single charging stock; accomplishing such objective by simple fractionation of such stock under any desired absolute pressure within the instrumentality of the indirect heat available from the subsequent liquid phase treatment; initially cracking the reduced stock from such simple fractionation in liquid phase, progressively cracking in like phase the recycle and clarified degraded stock thereby obtained; initially cracking selected intermediate distillate from such liquid phase cracking, in vapor phase, progressively cracking in like phase, selected intermediate distillate therein obtained; initially applying direct heat to the zone of liquid phase cracking, progressively applying the indirect and waste energy from such initial direct application to the other phases described and/or further refinement; and generally conducting such treatment with maximum economic heat interchange and minimum radiation loss.

90 In order that the invention may be the more readily understood, reference is made to the accompanying drawings, which are identically numbered wherein the same parts occur.

105 Fig. 1 and 1a is a general vertical elevation, essentially diagrammatic in character, rather than an exact representation of instrumentalities, of apparatus adapted for carrying out the invention.

110 In the accompanying drawings, 1 represents a pressure still designed for cracking in liquid phase, comprising a bank of tubes 2, connecting front and rear cross drums 3 and 4, the latter being subjacent and connected to front and rear 115 sluiceways 5 and 6, themselves also subjacent and connected to a horizontal bulb supply drum 7; the whole forming a closed system of freely connecting channels. The still 1, is further provided with the usual accessories; liquid level gauge 8, safety valves 9, 9', pressure gauge 10, and recording pyrometer 11; the vapor line 12, leading to reflux tower 13. From the base of the tower 13, the reflux line 14, enters the rear end of the still 1; the latter and the reflux tower 13 being in unrestricted connection with each other.

120 Continuous charging of the still 1 through the reflux tower 13, is effected by a high pressure hot oil pump 15, taking suction from the insulated supply tank 16 and adsorptive mixing tank 17 125 through the lines 18 and 19, controlled by stop valves 18' and 19' respectively, and discharging through line 20 past check valve 21 to top of reflux tower; while continuous withdrawal of the degraded still contents is accomplished through the line 22, as controlled by valves 23, 23', 23'', and automatic relief valve 24 to low pressure vapor separator 25, which may be by-passed if required, by proper manipulation of valves 23', 23'' and 130 26. Provision for emergency or complete discharge of still is afforded through line 26, past stop valve 27, to emergency cooler 28.

135 Continuous positive liquid cyclic circulation of the reacting liquid in still 1, is maintained by propeller 29, located in rear sluiceway 6; such propeller being mounted on shaft 30, extending 140

145 150

through stuffing box 31, and operated by motor 32. The furnace 33, over which the still assembly 1 is erected, may be heated by any desirable means; a typical arrangement for oil and gas fuel being respectively shown by burners 34 and 34'. The waste heat gases from the furnace 33 escape through the port 35, entering the vapor phase cracking furnace 36, and leave therefrom by the duct 37, breeching 38 and thence by the underground flue 39, finally passing to the atmosphere through the stack 40.

While straight crude or other gasoline containing hydrocarbon, may be initially employed for charging purposes, and the cracking still operated under atmospheric pressure until a sufficient quantity of natural gasoline has been vaporized, and enough reduced stock accumulated in the body of the still to admit of imposing cracking conditions; the continuous operation of the system may be hastened by initially employing reduced crude or other hydrocarbon, free from light material, as a charging medium.

As soon as the desired operating pressure has been built up in the still 1, and the contents thereof have reached the desired temperature, continuous charging thereto of heavier hydrocarbons and release of degraded still contents therefrom, is begun.

The crude gasoline vapors from the reflux tower 13, maintained under full still pressure, pass through the vapor line 41 to the dephlegmating tower 42, the control of vapor flow thereto being effected by proper manipulation of valves 43, 43', 44, 44' and/or 45 for remote regulation; or tower may be by-passed for emergency purposes by opening stop valve 44', permitting vapor to flow through lines 41 and 103, direct to condenser section 47, located in water cooled condenser box 48; the condensed gasoline accumulating in receiving tank 49, from whence it is automatically discharged from the system through the balanced valve 50, actuated by float mechanism 50'. The receiving tank 49 and condenser section 47, being in unrestricted communication with each other, are maintained at a constant pressure less than the apparatus preceding, by the automatic gas relief valve 49', regulated for the desired point of release. The waste permanent gas escaping through valve 49' flows through line 51 to gas burners 34', or other point of demand.

The vapor lines 52 and 53 serve to conduct the hot recycle stock vapors released in low pressure vapor separator 25, to the crude dephlegmating tower 54, control of recycle vapor flow thereto, being effected by proper adjustment of valves 55 and 55'; or by a different setting of same, the tower 54 may be by-passed to any desired degree, and the hot recycle vapors successively conducted to the heat exchangers 56, 57 and 58, with individual flow of vapor thereto controlled by proper manipulation of the valve nests 59, 59', 59''; 60, 60', 60'' and 61, 61', 61'' respectively, in a manner that will be apparent to one skilled in the art. The hot condensed recycle stock from the last exchanger employed, is normally conducted by lines 52 and 62, through adjustment of valves 63 and 63', to the insulated supply tank 16; or by a different adjustment of the same valves, the recycle stock may flow to condenser section 64, provided with a receiving tank and control mechanism similar to condenser section 47.

The further reduced degraded stock from the low pressure vapor separator 25, together with the partially coagulated, therein suspended com-

plex of hydrocarbon polymerides, free carbon and adsorptive coagulant, flows through lines 66 and 22, as controlled by stop valve 65 to valve nest 67, 67', 67'', controlling admission to, or by-passing of, heat exchanger 68; the stock then passing by lines 69 and 70 to filters 71, 72 and 73, with inlets thereto controlled by valves 71', 72' and 73' respectively; the clarified filtrate therefrom, flowing through line 74, as controlled by valves 71'', 72'' and 73'' to the insulated supply tank 16 for further treatment.

The waste products of filtration pass from the system by line 75, as controlled by valves 76, 76', and 76'' respectively; or the filters may be bypassed by opening valve 77, the degraded stock then flowing by line 78 to emergency cooler 28. If desired, a centrifuging, filter press or settling device may be substituted for the filters shown.

As soon as hot recycle stock vapors from the low pressure vapor separator 25 are produced in sufficient quantity to effect partial vaporization of the natural gasoline content of the prime charging stock (crude or other medium containing light ends), continuous charging of the latter is begun through line 79, by a low pressure pump 79'.

The prime charging stock first enters the heat exchanger 80, located in insulated supply tank 16, and heated initially by the hot clarified reduced stock flowing from filters 71, 72, and 73, or other clarifying device, and progressively by a mixture thereof with the hot reduced crude and condensed recycle stock continuously flowing to such supply tank when the process is in full operation. Control of flow of the prime charging stock through exchanger 80 is effected by the valve nest 81, 81' and 81''; the charging stock then entering exchanger 82, where it is further preheated by the hot reduced stock flowing from the crude dephlegmating tower 54, as soon as the latter is brought into the scope of operation. Control of flow through exchanger 82 is effected by valve nest 83, 83' and 83''; the preheated prime charging stock then entering top of crude dephlegmating tower 54, where the descending stream is brought into direct contact with the hot recycle stock vapors and free steam, preferably superheated, entering through valves 55' and 84 respectively.

The natural gasoline separated by such treatment escapes from tower 54, through line 85, to condenser sections 86 and 86', provided with a similar receiving tank and control mechanism to section 47. The reduced prime charging stock formed in tower 54, escapes therefrom through line 87, to exchanger shell 82', and thence by line 87' to insulated supply tank 16. The gasoline from tower 54 may enter the blending tower 88 through line 85', by proper manipulation of valves 89 and 89', or it may be subjected to other refinement as desired.

The vapor line 90 serves to conduct the dephlegmated gasoline vapor from tower 42, to condenser section 91, such section being similarly equipped with receiving tank and controls in a manner previously described. If desired, the vapor from tower 42 may enter the blending tower 88 through line 90', as controlled by the valves 92 and 92', or such vapor may be subjected to other refinement if required.

The heavier vapors condensing in tower 42 are reboiled in the lower portion thereof, through the instrumentality of the heat exchanger 57, with hot recycle stock vapors as a heating medium; control of flow through such exchanger being

effected through the previously described valve nest 60, 60' and 60''. The final condensate from tower 42 may pass by lines 93, 93' and 93'' to circulating pump 94, or such condensate may flow by lines 93, 95 and 95' to condenser section 96, similarly equipped as previously described in connection with condenser section 47. The direction of flow of the condensate in question is effected by proper setting of the valve nests 97, 97', 97'' and 98, 98', 98'' respectively, a constant liquid level being maintained in tower 42 by balanced valve 99 and float mechanism 99'.

The circulating pump 94 forces the condensate flowing thereto, past check valve 100, and through line 100 to vaporizing chamber 68', wherein such condensate is substantially vaporized under a pressure correlative to the vaporization obtained; such vaporization being effected through the agency of the heat exchanger 68, with hot degraded stock from the low pressure vapor separator 25 as a heating medium; control of liquid level in such vaporizing chamber being accomplished by balanced valve 101 and float mechanism 101'.

25 The vapor line 102 conducts the substantially vaporized intermediate, usually of a distillate nature, from the vaporizing chamber 68' to the vapor phase converting zone, the crude anti-knock gasoline therein produced in a manner described in a copending application, returning by the lines 103 and 103' to the vapor phase dephlegmating tower 104, with the vapor flow thereto being controlled by the valve nest 105, 105' and 105'' and/or 106 for remote regulation; or tower 30 may be by-passed as an emergency measure, by opening valve 107, permitting direct passage to condenser section 47.

The dephlegmated anti-knock gasoline vapor separated in dephlegmating tower 104, escapes 40 therefrom by line 108, and may pass direct to condenser section 110, similarly equipped as previously described, or it may enter blending tower 88 through line 109; the direction of flow being governed by proper setting of valves 111 and 111'; or such gasoline may be subjected to other refinement as desired:

45 The heavier vapors condensing in tower 104 are reboiled in the lower portion thereof, through the instrumentality of the heat exchanger 58, with hot recycle stock vapors as source of heat supply; control of flow through such exchanger being effected by the previously described valve nest 61, 61' and 61''. The final condensate from tower 104 may pass by lines 112, 93', 93'' to circulating pump 94 for subsequent progressive vapor phase treatment, or such condensate may flow by lines 112, 95 and 95' to the previously described condenser section 96. The direction of flow of the condensate in question is effected by proper setting of the valve nests 97, 97', and 97'' and 98, 98', 98'' in a manner previously described; a constant liquid level being maintained in tower 104 by balanced valve 113 and float mechanism 113'. The final dephlegmated blended gasoline vapor from blending tower 88 escapes through vapor line 114 to condenser sections 115 and 115', similarly equipped as previously described; or such gasoline may be subjected to further treatment in vapor phase, or other method of refinement. The heavier vapors condensing in blending tower 88 may be reboiled in the lower portion thereof through the instrumentality of the heat exchanger 56, with hot recycle stock vapors as a means of heat; control of flow through such exchanger being effected by the previously men-

tioned valve nest 59, 59' and 59''. The final condensate from tower 88 may flow by the line 116 to condenser section 117 equipped as previously described, or such condensate may pass by lines 116', 93' and 93'' to circulating pump 94, for subsequent progressive vapor phase treatment; the direction of flow of such condensate being effected by proper manipulation of the valves 118 and 118'. A constant liquid level is maintained in the tower 88 by balanced valve 119 and float mechanism 119'.

50 To generally secure efficient operation of the process, automatic temperature and pressure controls, recording and/or indicating thermometers and pressure gauges, and other devices of like order are employed whenever their use is desirable, although such apparatus may not be specifically mentioned or shown in the accompanying drawings. Similarly all instrumentalities involving the application of heat and transfer thereof, are so insulated as to secure maximum economic heat conservation, though not so shown in the accompanying drawings or described in the above specification.

55 The vapor phase converter, whose description is covered in a co-pending application, may be erected within the furnace zone proper of the main liquid phase cracking still, or constructed in a separate chamber without the system, but heated by the waste gases therefrom; and the steam supplied to the process may receive its necessary degree of super heat from the waste heat gases discharging from the vapor phase conversion zone, irrespective of the location of the latter.

60 What we claim is new and desire to protect by Letters Patent is:

1. A process for the production of gasoline from hydrocarbon oils which includes the steps of heating said hydrocarbon oils to distill off light constituents including gasoline existing therein, fractionally condensing and separating out heavier ingredients from said gasoline vapors so distilled, thereafter subjecting said hydrocarbon oils to a cracking reaction under pressure in the liquid phase to evolve additional gasoline and other oil vapors therefrom, condensing the heavier portions of the evolved vapors in two stages, returning the condensate from the first stage to the hydrocarbon oils subjected to said cracking reaction in the liquid phase, retaining separate the condensate from the second stage, withdrawing residual oils from said cracking reaction, reducing pressure on the oils so withdrawn while the latter are in a heated condition to flash a portion thereof into hot vapors, passing a portion of said hot vapors in heat interchange with said hydrocarbon oils before subjecting them to said cracking reaction to heat said hydrocarbon oils and distill off said light constituents as aforesaid, passing a portion of the unvaporized residual oils in heat interchange with the aforesaid heavier ingredients and condensate from the second stage to effect a substantial revaporization thereof, thereafter subjecting the resulting vapors to a cracking reaction in the vapor phase, and separately fractionating vaporized oil products from said vapor phase cracking reaction to obtain gasoline vapors and heavier liquid condensates.

65 2. A process for the production of gasoline from petroleum hydrocarbon oils which comprises heating a mass of hydrocarbon oils to a cracking temperature under pressure in the liquid phase to evolve vapors therefrom; separating and removing vapors so evolved to a fractionating zone and

- therein condensing out a heavy condensate portion; conducting the remaining vapors to a dephlegmating zone and therein separating out heavier fractions from said vapors as a condensate; removing the condensate thus formed to a vaporizing zone; withdrawing residual oils from said mass of hydrocarbon oils undergoing cracking; reducing pressure on the residual oils so withdrawn while said oils are in a heated condition thereby flashing a portion thereof into hot vapors; passing the unvaporized residual oils in indirect heat interchange with said condensate in said vaporizing zone thereby heating said condensate to less than a cracking temperature and effecting a substantial revaporization without cracking thereof; thereafter subjecting the resulting vapors to further heating at a cracking temperature for a time sufficient to crack said vapors in the vapor phase; removing vaporized oil products from said vapor phase cracking reaction to a separate fractionating zone; and fractionating therein out of contact with other oil products said vaporized oil products to obtain anti-knock gasoline vapors and heavier liquid condensates. 80
- 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130 131 132 133 134 135 136 137 138 139 140 141 142 143 144 145 146 147 148 149 150
3. A process for the production of gasoline from petroleum hydrocarbon oils which comprises heating a mass of hydrocarbon oils to a cracking temperature under pressure in the liquid phase to evolve vapors therefrom; separating and removing vapors so evolved to a fractionating zone and therein condensing out a heavy condensate portion; conducting the remaining vapors to a dephlegmating zone and therein separating out heavier fractions from said vapors as a condensate; removing the condensate thus formed to a vaporizing zone; withdrawing residual oils from said mass of hydrocarbon oils undergoing cracking; reducing pressure on the residual oils so withdrawn while said oils are in a heated condition thereby flashing a portion thereof into hot vapors; passing the unvaporized residual oils in indirect heat interchange with said condensate in said vaporizing zone thereby heating said condensate to less than a cracking temperature and effecting a substantial revaporization without cracking thereof; thereafter subjecting the resulting vapors to further heating at a cracking temperature for a time sufficient to crack said vapors in the vapor phase; removing vaporized oil products from said vapor phase cracking reaction to a separate fractionating zone and fractionating therein out of contact with other oil products said vaporized oil products to obtain anti-knock gasoline vapors and heavier liquid condensates; and introducing said heavier liquid condensates into said vaporizing zone whereby said condensates are revaporized and returned to the vapor phase cracking reaction heretofore mentioned. 100
4. A process for the production of gasoline from petroleum hydrocarbon oils which comprises heating a mass of hydrocarbon oils to a cracking temperature under pressure in the liquid phase to evolve vapors therefrom; separating and removing vapors so evolved to a fractionating zone and therein condensing out a heavy condensate portion; conducting the remaining vapors to a dephlegmating zone and therein separating out heavier fractions from said vapors as a condensate leaving in the vapor state gasoline vapors formed in the liquid phase cracking reaction; removing the condensate thus formed to a vaporizing zone; withdrawing residual oils from said mass of hydrocarbon oils undergoing cracking; reducing pressure on the residual oils so withdrawn while said oils are in a heated condition thereby flashing a portion thereof into 110
5. A process for the production of gasoline from petroleum hydrocarbon oils which comprises initially distilling and separating gasoline fractions from said hydrocarbon oils; thereafter heating the unvaporized portion of said hydrocarbon oils to a cracking temperature action under pressure in the liquid phase to evolve additional gasoline and other oil vapors therefrom; conducting vapors so evolved to a dephlegmating zone and therein separating out heavier fractions from said vapors as a condensate leaving in the vapor state gasoline vapors formed in the liquid phase cracking reaction; removing the condensate thus formed to a vaporizing zone; withdrawing residual oils from said hydrocarbon oils undergoing cracking; reducing pressure on the residual oils so withdrawn while said oils are in a heated condition thereby flashing a portion thereof into hot vapors; passing a portion of said hot vapors into direct physical contact with the hydrocarbon oils prior to cracking thereof to distill off said gasoline fractions as aforesaid; passing the unvaporized residual oils in indirect heat interchange with said condensate in said vaporizing zone thereby heating said condensate to less than a cracking temperature and effecting a substantial revaporization without cracking thereof; thereafter subjecting the resulting vapors to further heating at a cracking temperature for a time sufficient to crack said vapors in the vapor phase; removing vaporized oil product from said vapor phase cracking reaction to a separate fractionating zone and fractionating therein out of contact with other oil products said vaporized oil products to obtain anti-knock gasoline vapors and heavier liquid condensates. 120
6. A process for the production of gasoline from petroleum hydrocarbon oils which comprises initially distilling and separating gasoline fractions from said hydrocarbon oils; thereafter heating the unvaporized portion of said hydrocarbon oils to a cracking temperature under pressure in the liquid phase to evolve additional gasoline and other oil vapors therefrom; conducting vapors so evolved to a dephlegmating zone and therein separating out heavier fractions from said vapors as a condensate leaving in the vapor state gasoline vapors formed in the liquid phase cracking reaction; removing the condensate thus formed to a vaporizing zone; withdrawing residual oils from said hydrocarbon oils undergoing cracking; reducing pressure on the residual oils so withdrawn while said oils are in a heated condition thereby flashing a portion thereof into 130
7. A process for the production of gasoline from petroleum hydrocarbon oils which comprises initially distilling and separating gasoline fractions from said hydrocarbon oils; thereafter heating the unvaporized portion of said hydrocarbon oils to a cracking temperature under pressure in the liquid phase to evolve additional gasoline and other oil vapors therefrom; conducting vapors so evolved to a dephlegmating zone and therein separating out heavier fractions from said vapors as a condensate leaving in the vapor state gasoline vapors formed in the liquid phase cracking reaction; removing the condensate thus formed to a vaporizing zone; withdrawing residual oils from said hydrocarbon oils undergoing cracking; reducing pressure on the residual oils so withdrawn while said oils are in a heated condition thereby flashing a portion thereof into 140
8. A process for the production of gasoline from petroleum hydrocarbon oils which comprises initially distilling and separating gasoline fractions from said hydrocarbon oils; thereafter heating the unvaporized portion of said hydrocarbon oils to a cracking temperature under pressure in the liquid phase to evolve additional gasoline and other oil vapors therefrom; conducting vapors so evolved to a dephlegmating zone and therein separating out heavier fractions from said vapors as a condensate leaving in the vapor state gasoline vapors formed in the liquid phase cracking reaction; removing the condensate thus formed to a vaporizing zone; withdrawing residual oils from said hydrocarbon oils undergoing cracking; reducing pressure on the residual oils so withdrawn while said oils are in a heated condition thereby flashing a portion thereof into 150

hot vapors; passing a portion of said hot vapors into direct physical contact with the hydrocarbon oils prior to cracking thereof to distill off said gasoline fractions as aforesaid; passing the un-
5 vaporized residual oils in indirect heat inter-
change with said condensate in said vaporizing
zone thereby heating said condensate to less than
a cracking temperature and effecting a substan-
10 tial revaporization without cracking thereof;
thereafter subjecting the resulting vapors to
further heating at a cracking temperature for a
time sufficient to crack said vapors in the vapor
phase; removing vaporized oil products from said

vapor phase cracking reaction to a separate frac-
tionating zone; fractionating therein out of con-
tact with other oil products said vaporized oil
products to obtain anti-knock gasoline vapors and
heavier liquid condensates; and blending out of
80 contact with said heavier liquid condensates gaso-
line fractions initially distilled from said hydro-
carbon oils prior to cracking thereof and gasoline
vapors formed in the vapor phase and liquid
phase cracking reactions heretofore mentioned.
